(57) CLAIM

The ornamental design for a wearable blanket hoodie with zippers and removable components, as shown and described.

DESCRIPTION

FIG. 1 is a front perspective view of a wearable blanket hoodie with zippers and removable components, according to the present invention;

FIG. 2 is a front elevation view of the wearable blanket hoodie with zippers and removable components of FIG. 1; FIG. 3 is a rear elevation view of the wearable blanket hoodie with zippers and removable components of FIG. 1; FIG. 4 is a left side elevation view of the wearable blanket hoodie with zippers and removable components of FIG. 1; FIG. 5 is a right side elevation view of wearable blanket hoodie with zippers and removable components of FIG. 1; FIG. 6 is a top view of the wearable blanket hoodie with zippers and removable components of FIG. 1;

FIG. 7 is a bottom view of the wearable blanket hoodie with zippers and removable components of FIG. 1;

FIG. 8 is a front elevation view of the wearable blanket hoodie with zippers and removable components with zippers connecting the hood, sleeves, and lower robe portion partially open; and,

FIG. 9 is a front elevation view of the wearable blanket hoodie with zippers and removable components with the hood, sleeves, and lower robe portion removed.

Broken lines, where present, illustrate portions of the wearable blanket hoodie with zippers and removable components that form no part of the claimed design.
